UNITED STATES PATENT OFFICE.

ALBERT HUNDT, OF KARLSHORST, GERMANY, ASSIGNOR TO GENERAL ELECTRIC COMPANY, A CORPORATION OF NEW YORK.

CONTROL OF CHOKE COIL WITH SWITCHING-IN TAP TRANSFORMER.

Application filed August 22, 1925, Serial No. 51,886, and in Germany September 4, 1924.

In order to effect the change-over from one switch step to the other in tap transformers for applying a step by step varying voltage to a translating device without interruption of the circuit, use has heretofore been made of a choke coil, the supply line for the translating device being connected to the mid-point of the winding of the choke coil, while the two ends of the winding are connected to two neighboring taps of the transformer. Thus half the load current flows continuously through the two portions of the winding and the step voltage is likewise halved. In the change-over from one step to the other one half of the choke coil is cut out and the entire current flows temporarily through the other half of the winding until the change-over is completed. With this switching method half the load current is interrupted and again cut in with considerable spark formation at the switch contacts, and the supply voltage is suddenly altered by the value of the step voltage. This disadvantage is remedied by the invention in that there is provided a relative movement between the magnetic material or core and the halves of the choke coil, as for example, by the provision of means whereby the magnetic material or core is mounted so as to be displaced and is pushed during the switching process out of one half of the coil into the other and vice versa.

The result of this is that the half of the choke coil in which the iron core is located can receive only a very slight current, while the greater portion of the current is compelled to flow through the other half of the choke coil. The voltage distribution takes place in reverse manner. The current is gradually forced by the movement of the iron core from the one half of the coil into the other, while the voltage distribution is gradually displaced in the contrary direction. Thus, in the change over only a very slight current is interrupted and cut-in again, and moreover the supply voltage is altered continuously.

Fig. 1 is a very simplified diagram of a motor control scheme in accordance with the invention, Fig. 2 is a diagrammatic representation of the manner in which the iron core of the choke coil is disposed in intimate relation with one half and then with the other half of the choke coil, Fig. 3 and

Fig. 5 are modifications of the arrangement of Fig. 2, Fig. 4 is a detail showing one method of varying the reactance of the halves of the choke coil alternately, and Fig. 6 is another detail showing in very simple diagram an arrangement whereby the step by step switching operations and the movements of the iron cores of the choke coil halves are synchronized.

Fig. 1 shows diagrammatically a step transformer, with the primary winding *l* and the secondary winding *m*, which feeds a motor *k*. By means of the switches *a* to *g* the two connected choking-coils *h* and *i* can be alternately connected to the switch steps I to VI.

If, for example, the switches *a* and *b* are closed, the voltage applied to the motor *k* is that of the switch step I. If it is desired to change over to the second switch step, the switch *a* is opened and the switch *c* closed.

Fig. 2 shows the choke coils *h* and *i* with the displaceable iron core *n*. If the core *n* is located, as shown, in the coil *h*, the load current flows through the switch *a* and the coil *i*, while there is very little current through the switch *b* and the coil *h*. If now the core *n* is pushed into the coil *i*, the current in coil *h* gradually increases and falls in the coil *i* in a similar manner until the core is completely pushed into the coil *i*, and practically the entire motor current flows in coil *h*. Simultaneously the voltage applied to the motor *k* has gradually increased by the voltage of the step I. The switch *a* can now be opened without the formation of sparks at the contact thereof and the switch *c* can be closed without the formation of sparks. Hereupon the same action with step II can be begun anew.

If now the opening and closing of the switches and the displacement of the iron core is positively controlled in a suitable manner, a continuous regulation of the supply voltage results almost without any interruption of current.

Instead of the iron core *n*, a hollow displaceable iron body *o* (Fig. 3) enclosing the coil *h* or the coil *i* can also be employed.

Further, the core *n* and the iron body *o* can also be employed simultaneously, whereby the reactance is still further diminished.

In Fig. 4 is shown the arrangement of two iron cores *p* and *q*, which for the same

purpose are suspended from a balance beam r and alternately dip into the coils h and i , respectively.

Fig. 5 shows a device in which the two coils h and i are enclosed by the two iron yokes t for the purpose of keeping as low as possible the reactance of the coil in which the core happens to be.

The arrangement described for single-phase current can naturally be suitably employed also for polyphase current.

In Fig. 6 I have shown in very diagrammatic form an arrangement whereby the movement of the cores for the choke coils is caused to proceed in accordance with the switching operation from one tap voltage to another. The controller 10, having the switch contacts a to g thereon arranged to close successively as the controller is turned, has mechanically connected thereto a cam 11 and another cam 12 which is driven from the cam 11. These cams have projections thereon which cooperate with the projection 13 on the walking beam r' so as to tilt the walking beam back and forth and thus move the cores p and q into and out of their respective choke coils as the controller is turned. The variation in the choking effect of each choke coil half is thus coordinated properly with the opening and closing of the switches a to g as set forth previously.

What I claim as new and desire to secure by Letters Patent of the United States, is:

1. A control for a translating device supplied with a variable voltage through taps of a transformer in which the translating device is connected to a point between two substantially similar connected choke coils and the ends of such coils are connected to tap switches in such manner that a progressive operation of the switches first places one of the similar connected choke coils in series with the translating device, then the choke coils across taps of the transformer, then the other of the choke coils in series with the translating device, characterized by the provision of

vision of means for alternately varying the reactance of the choke coils as the switches are progressively operated for the purpose specified.

2. A control for a translating device supplied with a variable voltage through taps of a transformer in which the translating device is connected to a point between two substantially similar connected choke coils and the ends of such coils are connected to tap switches in such manner that a progressive operation of the switches first places one of the similar connected choke coils in series with the translating device, then the similar connected choke coils across taps of the transformer, then the other of the similar connected choke coils in series with the translating device, characterized by the provision of magnetic material associated with said coils and means for producing relative movement between said coils and said material to alternately vary the reactance of said coils as the tap switches are progressively operated, for the purpose specified.

3. A control for a translating device supplied with a variable voltage through taps of a transformer in which the translating device is connected to a point between two substantially similar connected choke coils and the ends of such coils are connected to tap switches in such manner that a progressive operation of the switches first places one of the choke coils in series with the translating device, then the choke coils across taps of the transformer, then the other of the choke coils in series with the translating device, characterized by the provision of a movable magnetic element for each of said coils and means for alternately moving said elements into and out of intimate relation with their respective coils as the tap switches are progressively operated, for the purpose specified.

In witness whereof, I have hereunto set my hand this 6th day of August, 1925.

ALBERT HUNDT.
